WILLIAM S. LOUCEE, OF ROCHESTER, NEW HAMPSHIRE, ASSIGNOR TO J. SPAULDING & SONS COMPANY, OF MILTON, NEW HAMPSHIRE, A CORPORATION OF NEW HAMPSHIRE.

SHOE-FORM.

1,087,884.

Specification of Letters Patent.

Patented Feb. 17, 1914.

Application filed May 27, 1908. Serial No. 435,274.

To all whom it may concern:

Be it known that I, WILLIAM S. LOUCEE, a citizen of the United States, residing at Rochester, in the county of Strafford and 5 State of New Hampshire, have invented certain new and useful Improvements in Shoe-Forms; and I do hereby declare the following to be a full, clear, and exact description of the invention, such as will enable others 10 skilled in the art to which it appertains to make and use the same.

The present invention relates to an improvement in shoe forms. Its object is to produce an improved form having an expanding heel portion, capable of being folded within the fore-part, and the invention consists in the shoe form hereinafter described and particularly defined in the 15 claims.

20 In the accompanying drawing illustrating the preferred form of the invention, Figure 1 is a side elevation of the form, and Fig. 2 a plan thereof.

The illustrated embodiment of the invention is described as follows:—The fore-part 25 1 is made of paper-board, leather-board, or the like, and provided at its lower edge with a lip or flange 2. The heel part consists of two bails, one of which bail 3 has its ends 30 pivoted at 4 on a rivet to the lower rear edge of the fore-part, and the other of which bail 5 is pivoted to the sides of the bail 3 at 6. These bails 3 and 5 are made of paper-board, leather-board or the like, and, together, 35 form the heel part of the form.

The form is inserted in a shoe with the heel part members collapsed, as shown in the dotted line indicated at 7; then the member 5 is pressed down into the heel portion of 40 the shoe with its lower edge resting on the sole or insole, after which the middle 8 of the member 3 is pressed down, whereby the toggle is straightened and the fore-part is thrust forward into the fore-part of the shoe 45 and the member 5 of the heel part is pressed back against the counter portion of the shoe. The two members 3 and 5 of the heel portion of the form act like a toggle in this operation and efficiently position the form in the 50 shoe. When it is desired to remove the form from the shoe, the middle portion of the member 3 is taken hold of and lifted, thereby collapsing the heel portion of the form and permitting it to be lifted so as to enable

the form to be removed easily from the 55 shoe.

The form, as thus far described, is easy of insertion in the shoe and removal therefrom, and at the same time, is adapted to be securely held in place in the shoe. An additional feature of the construction resides in the fact that the heel portion of the form may be folded within and entirely embraced by the fore-part, by turning it to the position indicated in the dotted line 9. This is 60 of advantage in certain uses of shoe forms, as, for example, in the manufacture of a shoe when it is desired to attach the heel, at which time the heel part can be folded within the fore-part and the shoe applied to 65 the anvil without removal of the form from the fore-part of the shoe.

The shoe form of the present invention is simple in construction, easily inserted in and withdrawn from the shoe, and enables the 70 heel to be attached without removal of the form during the process of nailing on the heel. This shoe form is adapted for use not only as a follower in the manufacture of 75 shoes, but also as a display form and as a 80 tree.

Having thus described the invention, what is claimed is:—

1. A shoe form comprising a hollow fore-part and a heel part pivotally connected thereto, the heel part consisting of two bails, the one pivotally connected at its free ends to the opposite sides of the fore-part, and the other extending outside of the first mentioned bail and having substantially the 90 shape of the heel counter so that it fits snugly within the shoe heel and pivotally connected at its free ends to the sides of first mentioned bail at points in the rear of the connections between the first mentioned 95 bail and the fore-part, said two bails forming a toggle which is pressed down into the shoe to extend it and force the fore-part forwardly into the shoe, the first bail folding inside of the second bail when the toggle 100 is straightened, substantially as described.

2. A shoe form comprising a hollow fore-part and a heel part pivotally connected thereto, the heel part consisting of two bails, one pivotally connected at its free ends to the 105 sides of the forepart and the other pivotally connected at its free ends to the sides of the first bail, said bails forming a toggle

for the purpose of shortening the form for insertion and removal from the shoe and being adapted to be folded within the hollow forepart while the form is within the interior of the shoe, substantially as described.

3. A shoe form comprising a hollow forepart having a rearward opening therein, and a heel part pivotally connected to the hollow fore-part near the lower edge of the rearward opening and within the mouth thereof, said heel part being smaller than the mouth of the opening so that the heel part may be turned up and folded through the opening entirely within the fore-part while the form is within the interior of the shoe, substantially as described.

4. A shoe form comprising a hollow forepart having a rearward opening therein, and a heel part pivotally connected to the lower portion of the fore-part near the edge of the opening and comprising a toggle for lengthening and shortening said heel part, said heel part being smaller than the opening and arranged to be turned up and folded through the opening entirely within the hollow fore-part while the form is within the interior of the shoe, substantially as described.

5. A shoe form comprising a hollow forepart having a rearward opening therein, and a heel part pivotally connected thereto and consisting of two bails, one pivotally

connected to the fore-part near the lower edge of said opening, and the other pivotally connected to the first mentioned bail so as to form a toggle for lengthening and shortening the heel part, said heel part being of less size than the mouth of the opening so that the heel part may be turned up and folded through the opening within the hollow fore-part while the form is within the interior of the shoe, substantially as described.

6. A shoe form comprising a hollow leather-board forepart and a heel part consisting of two bails of leather-board, the one pivotally attached at its ends to the opposite rear sides of the forepart, and the other pivotally attached to the opposite sides of the first mentioned bail and extending outside of and beyond the same, the two bails of said heel part forming an expanding and shortened toggle for expanding the heel part to cause the form to be lengthened to fit the shoe and for contracting the heel part to cause the form to be shortened to be withdrawn from the shoe, substantially as described.

In testimony whereof I affix my signature, in presence of two witnesses.

WILLIAM S. LOUGEY.
